CLAIM

The ornamental design for a table top, as shown and described.

DESCRIPTION

FIG. 1 is a perspective view of a first embodiment of the table top showing my new design as applied to a table; FIG. 2 is a front elevational view thereof, the opposite side of which is identical;

FIG. 3 is a right side elevational view thereof, the opposite side of which is identical;

FIG. 4 is a top plan view thereof;

FIG. 5 is a bottom plan view thereof;

FIG. 6 is a perspective view of a second embodiment of the table top showing my new design as applied to a table;

FIG. 7 is a front elevational view thereof, the opposite side of which is identical;

FIG. 8 is a right side elevational view thereof, the opposite side of which is identical;

FIG. 9 is a top plan view thereof; and,

FIG. 10 is a bottom plan view thereof.

The broken line portions of the drawings are included to show portions of the article that form no part of the claimed design and represent environmental structure only.

1 Claim, 6 Drawing Sheets
